UNITED STATES PATENT OFFICE.

THOMAS A. HORTON, OF KINGSTON, NEW YORK.

CIGAR MACHINE.

Application filed August 28, 1925. Serial No. 53,081.

My invention relates to cigar machines and more particularly to improved devices for feeding or delivering a hand-made bunch to the binder-applying mechanism. In 5 cigar-making machinery heretofore used it has been customary to employ certain operating means in making or forming the bunch which do not follow hand operations as is the case in the wrapper-applying machinery. 10 The usual method for making or forming a bunch by putting together the filler for the foundation of a cigar has utilized a trough or travelling belt in or on which the filler is placed. The filler load has then been cut 15 off or out by knives which produce short pieces or scrap thereafter to be placed in the filler load for purposes of economy. Such replacement, however, is likely to cause the stoppage of the air passages in the filler load 20 thereby preventing a free draft in the completed cigar when smoked.

The objects of my invention are, among other things, to provide an improved feeding attachment for hand-made bunches in 25 which short pieces of filler and scrap are entirely eliminated, and also to provide novel and improved mechanisms whereby the hand-made bunches are successively formed of proper length and thickness without the 30 necessity of straightening the filler and are thereafter delivered to the binder-applying machinery substantially as the filler load is formed by hand. A further feature is the provision of means by which the bunch is 35 delivered so that the filler load is springy and not compressed and hard in spots as is likely to be the case when the filler load is chopped out by knives.

According to my invention, a pair of 40 reciprocating cups or molds are used to form and carry the hand-made bunches which molds are alternately brought to discharging position. These molds not only act to carry the hand-made bunch undisturbed to the 45 point of discharge, but also serve to guide the operator in making the filler load of the right length, the desired shape and proper thickness, different sets of molds of varying sizes being employed according to requirements. Furthermore I have provided novel 50 means comprising slideable fingers coacting with the discharging plunger for holding the hand-made filler load undisturbed while the discharge plunger is withdrawn from the 55 mold and is returning to its original raised position after having pushed the load onto

the delivery table to be advanced to the binder-applying mechanism.

My improved cigar-machine also embodies other features of novelty and improvement 60 in combination with the binder and wrapper-applying mechanism whereby the operating parts are simplified and made more effective and otherwise better adapted for use, all of which will be hereinafter set forth 65 and then particularly pointed out in the appended claims.

Figure 1 is a top plan view of a part of the cigar machine embodying my invention 70 in a preferred form;

Figure 2 is a view in front elevation showing the operating mechanism;

Figure 3 is an enlarged front elevation in section, the section being taken on the line 3—3 of Figure 1, and showing the bunch 75 discharge operating mechanism;

Figure 4 is an enlarged sectional view in side elevation taken on the line 4—4 of Figure 3;

Figure 5 is a section taken on line 5—5 of 80 Figure 3 showing the finger operating cam;

Figure 6 is a top plan view of the bunch discharging mechanism;

Figure 7 is an enlarged section in front elevation taken on the line 7—7 of Figure 85 6 showing the bunch in position to be discharged from the table;

Figure 8 is a section in front elevation taken on the line 8—8 of Figure 7, the arrows showing the discharging movement of 90 the pusher; and

Figure 9 is an enlarged detail view on the line 9—9 of Figure 2.

Similar numerals refer to similar parts throughout the several figures.

Referring more particularly to Figs. 1 and 2 the side-frames 10 and 11 resting on the floor 12 support the table 13 in horizontal position. Journalled in the side-frames 10 and 11 is the main power-shaft 14 driven by 100 the sprocket 15 over which passes the drive-chain 16 which engages the drive-sprocket 17 rotated by any suitable source of power, for example, the electric motor 18 set on the floor 12. Mounted on the table 13 and supported at either end by the blocks 19 and 20 are the two sets of mutually parallel rails 21, 22 and 23, 24 maintained in position at either end by the blocks 25 and 26 to which such rails are affixed to form the transverse 105 track or run-way 27 for the two cups or molds 28 and 29 which are of similar con-

struction and are adapted to form and carry the hand-made filler loads 30 to the binder-applying mechanism to complete the bunch. The cups or molds 28 and 29 are slidably held between the four rails 21, 22 and 23, 24 (Figs. 2 and 4), and are alternately and successively brought to the middle portion of track or run-way 27 opposite the delivery to the binder-applying mechanism which 10 forms no part of my improved attachment.

The means for reciprocating the molds 28 and 29 in the track 27 may be widely varied. In the present embodiment, the molds 28 and 29 carry the rearwardly projecting lugs 31 and 32 respectively pivoted to the outer bent ends 33 and 34 of the respective rock-arms 35 and 36 journaled on pins 37 and 38 attached to brackets 39 and 40 respectively which are suitably affixed to the table 13 as shown in Figs. 1 and 2. To support the outer ends 33 and 34 of the arms 35 and 36 I have provided the segmental rails 41 and 42 which are suitably secured to the top surface of the table 13 and on which rails 20 run the rollers 43 and 44 pinned to the depending brackets 45 and 46 attached to the under sides of the arms 35 and 36 respectively as shown in Figs. 1 and 2.

The rock-arms 35 and 36 are actuated in 30 suitable timed relation with each other by the cylindrical cams 47 and 48 secured to the ends of the power-shaft 14 outside the side-frames 10 and 11 respectively. The cams 47 and 48 are respectively engaged by 35 the cam-rollers 49 and 50 pivoted to the lower ends of the rock-levers 51 and 52 which are fulcrumed on the brackets 53 and 54 affixed to the side frames 10 and 11 respectively as shown in Fig. 2. Pinned to the upper ends of the rock-levers 51 and 52 are the blocks 55 and 56 which have universal joint connections 57 and 58 with the free ends of the links 59 and 60 pinned to the rock-arms 35 and 36 respectively as clearly shown in 45 Fig. 1. The cams 47 and 48 are so set on the power-shaft 14 that when the mold 28 is in its Fig. 1 position at the end of the track 27, the mold 29 is in discharging position midway across the table 13, and when the mold 29 is in its retracted position at the right-hand end of the track 27 (Fig. 1), the mold 28 will occupy the center position on the table 13. Stops 61 and 62 having their 50 suitably adjustable set-screws 63 and 64 respectively are affixed to the top of the table 13 to control and limit the forward strokes of the two rock-arms 35 and 36 so that the molds 28 and 29 may be brought to rest in accurate alinement with the discharge mechanism for subsequent delivery to the wrapper-applying mechanism.

The molds 28 and 29 are elongated trough-shaped with open-bottoms 65 to enable the 60 filler-loads 30 carried therein to be discharged from the molds 28 and 29 when the

latter are alternately brought to discharging position in the middle of the table 13. The inner spaces of the molds 28 and 29 may be of different lengths and widths, depths and shapes to provide for cigars of different sizes, and it is customary to provide several sets of molds of such varying sizes for use when forming the respective bunches for such cigars of different sizes.

After the filler-loads 30 have been brought to discharging position, they must be removed from the molds 28 and 29 without disturbing the filler which has heretofore been formed by the operators and loaded in the two molds 28 and 29 when at rest at the two ends of the track 27. Such mechanism may be widely varied in structure and operation. In the present embodiment the plunger 66 is formed with depending spaced-apart lugs 67 (Figs. 2 and 3), and is mounted on bars 68 and 69 detachably secured to the cross-plate 70 by nuts 71 and 72 respectively. The cross-plate 70 is secured to the bent-over ends of the slidable rods 73 and 74 journaled in the vertically-disposed sleeves 75 and 76 secured in the table 13 back of the track 27 as shown in Figs. 1 and 2. The rods 73 and 74 are reciprocated in unison by cam-rollers 75 and 76 pivoted on the pins 77 and 78 secured to the lower ends of the rods 73 and 74 respectively as shown in Figs. 1, 2 and 9. The cam-rollers 75 and 76 engage the box-cams 79 and 80 mounted on the inner ends of the cross-shafts 81 and 82 journaled in the brackets 83 and 84 respectively affixed to the under side of the table 13, and also respectively journaled to the side-frames 10 and 11 as shown in Figs. 1 and 2. The shaft 81 is driven from the power-shaft 14 by the chain 85 passing around sprockets 86 and 87 respectively affixed to the shafts 14 and 81, while the shaft 82 is also driven from the shaft 14 by the chain 88 passing around sprockets 89 and 90 respectively affixed to the shafts 14 and 82. The cams 79 and 80 actuate the rods 73 and 74 in unison and are so timed that the plunger 66 is lowered to discharge the filler-load 30 from either mold 28 or 29 onto the table 13 as soon as the mold is brought to its mid-way position, the lowered plunger 66 being shown by dotted lines in Fig. 3.

After the filler-load 30 has been discharged or removed from the molds 28 and 29, it is necessary to provide means for holding the hand-made filler-load undisturbed while the plunger 66 is withdrawn or raised, and also to provide suitable devices to push or advance the successive individual filler-loads along the table 13 to be carried to the binder-applying mechanism. Such means may be widely varied in structure: In the present embodiment shown in detail in Figs. 6, 7 and 8, the slotted tracks 91 and 92 mounted in parallelism on the table 13 carry 125

the horizontal-reciprocable slides 83 and 94, respectively which are connected by the cross-plate 95. Secured to the top of the plate 95 are the forwardly-projecting fingers 96 (five in number being shown) which are adapted when in their forward position to pass between the lugs 67 of the lowered plunger 66 to hold the filler-load 30 in undisturbed position on the table 13 when the plunger 66 is raised. Affixed to the plate 97 secured to the under side of the rail 24 are five spaced-apart fixed fingers 98 arranged to coact with the sliding fingers 96 to hold the filler-load 30 as the latter is pushed forward or advanced along the table 13 (Fig. 8). The fingers 98 are disposed so as to be slightly out of transverse alinement with the fingers 95 so that each pair of fingers 95 and 98 will slidably coact with each other when the fingers 95 are advanced as shown in Figs. 6 and 7.

The mechanism for operating the slides 93 and 94 in the tracks 91 and 92 is as follows: The slides 93 and 94 carry the slotted brackets 99 and 100 which are engaged by the pins 101 and 102 mounted on the free ends of the bell-crank levers 103 and 104 fulcrumed on the studs 105 and 106 affixed to the table 13. The bell-crank levers 103 and 104 are actuated by the slide-bars 107 and 108 which are mounted on brackets 109 and 110 respectively secured to the under side of the table 13 (Figs. 3 and 4). Each slide-bar 107 and 108 carries spaced-apart pins 111 and 112 projecting upwardly through transverse slots 113 and 114 formed in the table 13 to engage the rounded ends 115 and 116 of the levers 103 and 104 respectively. The slide-bars 107 and 108 are actuated in unison by the following mechanism: Pinned to the under side of the slide-bar 107 is the upper arm of the rock-lever 117 fulcrumed at 118 to the bracket 109; the rock-lever 117 is pivotally connected by the link 119 to the arm 120 of the bell-crank lever 121 fulcrumed at 122 to the bracket 110 with the arm 120 pinned to the slide-bar 108 as shown in Figs. 3 and 4. The bell-crank lever 121 is pivotally connected by the rod 123 to the rock-arm 124 pinned to the stub-shaft 125 secured in the bracket 126 affixed to the table 13. The rock-arm 124 carries the cam-roller 127 which engages the box-cam 128 mounted on the cam-shaft 129 journaled in the bracket-bearings 130 and 131 respectively as shown in Fig. 1. The cam-shaft 129 is driven from the power-shaft 14 by the chain 132 passing around the sprockets 133 and 134 secured to the shafts 14 and 129 respectively. The cam 128 is so timed as to operate the bell-crank levers 103 and 104 to advance the slides 93 and 94 just after the plunger 66 has been lowered to discharge the filler-load 30 from either mold 28 or 29 on the table 13.

Means are provided to push forward or advance the filler-load 30 when discharged from the mold (Figs. 6, 7 and 8) from beneath the track 27 to the delivery end of the usual wrapper-applying mechanism. In 70 the present embodiment the transverse pusher 135 is supported adjacent the slotted plate 136 fitted in the cut-out portion 137 of the table 13. The pusher 135 is mounted on the post 138 which is secured to the bar 139 75

slidably mounted in the guide 140 secured to the sleeve 141 carried by the depending bracket 142 affixed to the under side of the table 13. The pusher 135 is raised and lowered as well as advanced and retracted in 80 regular cycles in order to carry the successive filler-loads 30 forwardly. The pusher 135 is raised and lowered by means of the bell-crank lever 143 fulcrumed on the stub-shaft 144 carried by the bracket 126 secured to the table 13, the arm 146 of the lever 143 being pivotally connected to the depending end of the guide 140 (Fig. 4) with the arm 147 carrying the cam-roller 148 which engages the cam grooves 149 formed in the 90 disk 150 mounted on the cam-shaft 129. The pusher 135 is advanced and retracted with the post 138 sliding in the slotted plate 136 by means of the rock-lever 151 fulcrumed on the stub-shaft 125 with its upper end pivotally connected to the link 152 pinned to the link 153 pivotally connected to the slide-bar 139. The short arm 154 of the lever 151 carries the cam-roller 155 which engages the cam grooves 156 formed 100 in the disk 150. The contours and timing of the cam grooves 149 and 156 are such that the pusher 135 has a compound discharging movement by first being raised above the level of the table 13 sufficiently to 105 clear same and is advanced forwardly under the already advanced fingers 96 and also the fixed fingers 98 to push the filler-load 30 out of the way for the next operation all as shown by the arrows in Fig. 8. Then the pusher 135 is withdrawn or retracted to the limit of its rearward stroke after which it is depressed within the cut-out portion 137 at the end of the cycle.

The operation of my improved attachment 115 in a cigar machine is substantially as follows: Operators are located on either side of the table 13 in proximity to the ends of the track 27 where they form the filler load or bunch 30 and deposit such hand-made 120 filler-loads in the molds 28 and 29, one operator serving the mold 28 while another operator serves the mold 29. During the operation of the machine the molds 28 and 29 are at the end of the track 27 during 125 the dwell of the cams 47 and 48 which is sufficiently long to enable the expert operator to gauge the proper length and thickness of the filler-load before placing same in the respective molds 28 and 29. The 130

molds 28 and 29 carrying the separate bunches are brought to their center discharging position by the action of the cams 47 and 48 as hereinbefore described. When the 5 mold 29 (for example) is brought to its Fig. 1 position with the rock-arm 36 against the set-screw 64, the plunger 66 is lowered by means of the cams 79 and 80 on the ends of the shafts 81 and 82 so as to travel from its full-line position to that shown by dotted lines in Fig. 3. The filler-load 30 is thereby forced out of the bottom of the mold 29 in the position shown in Figs. 7 and 8 on the slotted plate 136. The 10 fingers 96 are then advanced by the action of the cam 128 through the openings between the lugs 67 to engage with the fixed fingers 98 to cover and hold the filler-load 30 intact and in position on the slotted 15 plate 136 at which time the plunger 66 is lifted to its original position shown by dotted lines in Fig. 8, and the mold 29 is retracted to the end of the run-way 27. While the fingers 96 are interlocked with 20 the fingers 98 as shown in Fig. 8, the pusher 135 is raised by the action of the cam groove 149 as shown by the vertical arrow in Fig. 8 after which the uplifted pusher 135 is advanced by the action of the cam groove 156 (to the right in Fig. 8) to engage the side 25 of the filler-load 30 to push the latter forwardly to the delivery end of the binder-applying mechanism; then the pusher 135 is first retracted or withdrawn (to the left in Fig. 8) and afterwards lowered to its 30 original position, at which time the mold 28 has been advanced to its center loading-discharging position. The cams 47 and 48 are so set to secure this alternate movement 35 of the molds 28 and 29 which are held stationary in their extreme left and right hand positions (Figs. 1 and 2) when being filled by hand. The action of the sliding fingers 96 in conjunction with the 40 fingers 98 as the former pass through the openings in the plunger 66 before the latter is raised from the mold enables the filler-load to be covered and maintained in exactly the same arrangement as it was deposited in the mold which enables my improved attachment to secure hand-made 45 bunches of uniformity in length, weight and thickness as well as of the shape required. The foregoing construction embodies the 50 principles of my improved attachment in a preferred form but many changes may be made in the form and arrangement of the parts without departing from the scope of my invention or in any way sacrificing its chief advantages, which comprise, among 55 others, the elimination of short pieces of scrap in the filler-load the saving of from one to two pounds of filler tobacco per one thousand cigars over present mechanical 60 methods in forming the bunch, and the op-

portunity of cigar manufacturers to mix uniformly in each cigar different grades of filler tobacco.

I claim as my invention:—

1. In a cigar machine, a run-way, a pair 70 of filler-load molds operable along said run-way, and means for moving each mold from an end to a common position in the middle portion of said run-way.

2. In a cigar machine, a run-way, a pair 75 of filler-load molds operable along said run-way, and means for reciprocating each mold in sequence relatively to the other from an end to a common position in the middle portion of said run-way. 80

3. In a cigar machine, two reciprocable 85 filler-load-molds and means for moving each of said molds from loading to discharging positions.

4. In a cigar machine, two reciprocable 90 filler-load-molds and means for moving each of said molds alternately from separate loading positions to a common discharging position.

5. In a cigar machine, a run-way, a pair 95 of filler-load molds each operable along said run-way, and means for reciprocating each mold to and from predetermined end positions to a common middle position in the run-way. 100

6. In a cigar machine, a run-way, two 105 filler-load-molds operable along said run-way, and means for reciprocating each of said molds to and from predetermined positions in the run-way. 110

7. In a cigar machine, a run-way, two 115 filler-load-molds operable along said run-way, and means for reciprocating each of said molds in sequence relatively to the other to and from predetermined positions in the 120 run-way. 125

8. In a cigar machine, a run-way, a pair 130 of filler-load molds operable along said run-way, and means for reciprocating each mold from an end to a common position in the middle portion of said run-way. 135

9. In a cigar machine, a run-way, two 140 filler-load-molds operable along said run-way, and means for reciprocating each of said molds from separate loading position 145 to a common discharging position. 150

10. In a cigar machine, a run-way, two 155 filler-load-molds operable along said run-way, and means for reciprocating each of said molds in sequence relatively to the other from separate loading positions to a common discharging position. 160

11. In a cigar machine, filler-load carriers 165 comprising a pair of trough-shaped molds each having an open bottom and transversely movable in straight-line alinement from loading and discharging positions. 170

12. In a cigar machine, filler-load carriers 175 comprising a pair of trough-shaped molds each having an open bottom and transversely 180

movable in straight-line alinement in sequence relatively to each other from loading and discharging positions.

13. In a cigar machine, two reciprocable 5 filler-load molds each having an open bottom, means for moving each mold from loading to discharging positions, and a discharge mechanism to force the load through said bottom of each mold when in discharging position.

14. In a cigar machine, two reciprocable 10 filler-load molds each having an open bottom, means for moving each mold from loading to discharging positions, and a vertically movable discharge mechanism to force the load through said bottom of each mold when in discharging position.

15. In a cigar machine, filler-load carriers 15 comprising a pair of trough-shaped molds each having an open bottom and transversely 20 movable in straight-line alinement from loading and discharging positions, and a vertically movable discharge mechanism to force the load through the bottom of each mold 25 in sequence relatively to the other when brought to a common discharging position.

16. In a cigar machine, a filler-load-mold 30 having an open bottom, a vertically movable discharge mechanism to force the load through said bottom when lowered there-through, and means bearing on the top of the load in discharged position when the discharge mechanism is raised.

35 17. In a cigar machine, a filler-load-mold having an open bottom, a vertically movable discharge mechanism to force the load through said bottom when lowered there-through; and horizontally extensible means 40 bearing on the top of the load in discharged position when the discharge mechanism is raised.

18. In a cigar machine, a filler-load-mold 45 having an open bottom, a vertically movable discharge plunger to force the load through the bottom when lowered and having spaced-apart openings therein, and means movable through said plunger openings to cover and hold the load in position when the plunger 50 is raised.

19. In a cigar machine, a filler-load-mold having an open bottom, a vertically movable discharge plunger to force the load through the bottom when lowered and having spaced-apart openings therein, and a series of fingers 55 slideable forwardly into said plunger openings to cover and hold the load in position when the plunger is raised.

20. In a cigar machine, a filler-load-mold 60 having an open bottom, a vertically movable discharge plunger to force the load through the bottom and having spaced-apart openings therein, means movable through said plunger openings to cover and hold the 65 load in position, and means for reciprocating

said last means in timed relation with said plunger.

21. In a cigar machine, a filler-load-mold having an open bottom, a vertically movable discharge plunger to force the load 70 through the bottom and having spaced-apart openings therein, a series of fingers movable through said plunger openings to cover and hold the load in position, and means for reciprocating said fingers in timed relation 75 with said plunger.

22. In a cigar machine, a filler-load-mold having an open bottom, a discharge mechanism therefor, means bearing on the top of said load to hold same when discharged, and 80 means for pushing said load from said discharged position.

23. In a cigar machine, a filler-load-mold having an open bottom, a vertically movable discharge mechanism to force the load 85 downwardly through said bottom, means bearing on the top of said load to hold same when discharged from the mold, and means for pushing said load from discharged 90 position beneath said holding means bearing on said load.

24. In a cigar machine, a filler-load-mold having an open bottom, a vertically movable discharge plunger to force the load through said bottom, means coacting with 95 said plunger to cover and hold the load in discharged position when the plunger is raised, and means for pushing said load from beneath said first-mentioned means.

25. In a cigar machine, a filler-load-mold 100 having an open bottom, a vertically movable discharge mechanism to force the load downwardly through said bottom, means bearing on the top of said load to hold same when discharged from the mold, and means operable in timed relation with said discharge mechanism for pushing said load 105 from discharged position beneath said holding means bearing on said load.

26. In a cigar machine, a filler-load-mold 110 having an open bottom, a vertically movable discharge plunger to force the load through said bottom, a series of fingers horizontally slideable and coacting with said plunger to hold the load in discharged position when the plunger is raised, and means for pushing said load from beneath said fingers.

27. In a cigar machine, a filler-load-mold 115 having an open bottom, a vertically movable discharge plunger to force the load through said bottom, a series of horizontally slideable fingers coacting with said plunger when lowered to cover and hold the load in discharged position, a pusher operable beneath said fingers, and means for advancing said pusher when said fingers are holding the load and said plunger is raised therefrom.

28. In a cigar machine, a filler-load-mold 120 having an open bottom, a vertically movable 125

130

discharge plunger to force the load through said bottom, a series of horizontally slideable fingers coacting with said plunger when lowered to cover and hold the load in discharged position, a pusher operable beneath said fingers, means for advancing said pusher when said fingers are holding the load and said plunger is raised therefrom, and means for withdrawing said fingers and said pusher.

29. In a cigar machine, a filler-load-mold having an open bottom, a vertically movable discharge plunger to force the load through said bottom, a series of horizontally slideable fingers coacting with said plunger when lowered to cover and hold the load in discharged position, a pusher operable beneath said fingers, means for advancing said pusher when said fingers are holding the load and said plunger is raised therefrom, and means for simultaneously withdrawing said fingers and said pusher.

30. In a cigar machine, a run-way, two filler-load-forming molds travelling in said run-way from loading to discharging positions, a vertically movable discharge plunger, means for lowering said plunger to discharge the load from said mold when either of said molds is brought to discharging position, means to cover and hold said discharged load in position beneath said mold, and means for carrying said load from beneath said plunger.

31. In a cigar machine, a run-way, two filler-load-forming molds having open bottoms travelling in said run-way from loading to discharging positions, a vertically

movable discharge plunger, means for lowering said plunger to discharge the load from said mold through said bottom when either of said molds is brought to discharging position, means to hold said discharged load in position beneath said mold, and means for carrying said load from beneath said plunger and said holding means.

32. In a cigar machine, a run-way, two filler-load-forming molds travelling in said run-way from loading to discharging positions, a vertically movable discharge plunger, means for lowering said plunger to discharge the load from said mold when either of said molds is brought to discharging position, a series of horizontally slideable fingers coacting with said plunger when lowered to hold said discharged load in position beneath said mold, and means for carrying said load from beneath said plunger.

33. In a cigar machine, a run-way, two filler-load-forming molds travelling in said run-way from loading to discharging positions, a vertically movable discharge plunger, means for lowering said plunger to discharge the load from said mold when either of said molds is brought to discharging position, a series of horizontally slideable fingers coacting with said plunger when lowered to hold said discharged load in position beneath said mold, and a horizontally reciprocating pusher for carrying said load from beneath said fingers when extended after the plunger is raised.

THOMAS A. HORTON.
